UNITED STATES PATENT OFFICE.

ISAAC PETERSON, OF BERKELEY, CALIFORNIA.

SPACING FASTENER FOR WIRE SCREENS.

Application filed September 17, 1924. Serial No. 738,256.

To all whom it may concern:

Be it known that I, ISAAC PETERSON, a citizen of the United States, and a resident of Berkeley, in the county of Alameda and State of California, have invented new and useful Spacing Fasteners for Wire Screens, of which the following is a specification.

The present invention relates to improvements in spacing fasteners for wire screens used as reinforcing elements for cement mixtures applied to the face of a house. To give to a house a stucco finish, it is customary to secure wire netting or a wire screen in spaced relation to the wall of the house so that on applying a coat of cement material, the wire screen becomes embedded in the material and reinforces the same. To hold the wire screen in spaced relation, various means have been designed and it is proposed in the present invention to provide a simple device for spacing individual strands of the wire netting or wire screen from the wall of the house, the device being particularly adapted to resist the blow of a hammer, and being formed with a flat base which presents no sharp corners and, therefore, does not cut into the tar paper ordinarily provided next to the wall and which, furthermore, presents a flat saddle for the strand of wire to rest in so that there is little danger of the wire being cut by the blow of the hammer. Further advantages of my device will appear as the specification proceeds.

The preferred forms of my invention are illustrated in the accompanying drawing, in which

Figure 1 shows two of my fasteners in operative relation with a wire screen;

Figure 2 a longitudinal cross-section through my fastener taken along line II—II of Figure 1;

Figure 3 a perspective view of my fastener;

Figure 4 a transverse section taken along line IV—IV of Figure 1, and

Figure 5 a perspective view of a slightly modified form.

While I have shown only the preferred forms of the invention, I wish to have it understood that various changes or modifications may be made within the scope of the claims hereto attached without departing from the spirit of the invention.

My spacing fastener as illustrated in Figures 1 to 4 comprises a tubular element 1

of substantially rectangular cross-section presenting a flat base 2, the two spacing sides 3 and a saddle shaped top element 4, the two spacing elements 3 converging 60 slightly toward the top element due to the fact that the latter is bent into the shape of a saddle. The nail 6 pierces the top element 4 and the base 2 through perforations 7 and 8 so that when the nail is driven 65 into the wall, it will cause the base to lie firmly against the wall and will, at the same time, confine a strand of wire in the saddle between the top element 4 and the head 9 of the nail. Instead of a single strand that 70 portion of the wire netting presenting a double strand, as shown at 11 in Figure 2, may, of course, be substituted. The two spacing elements 3 are preferably indented, as shown at 12, to offer more resistance to 75 collapse due to the blow of the hammer. In the form shown in Figure 5, a double base 13 consisting of the two elements 14 and 16, is provided, which renders the device somewhat stronger and which is manufactured in a somewhat different manner, the fastener shown in Figure 3 being cut 80 from a previously prepared tube, while the fastener shown in Figure 5 is bent into shape from a previously prepared strip of 85 metal.

The advantages of the device are apparent. The base being flat, there is no danger of the same cutting into the tar paper secured next to the wall, nor is there 90 any danger of the base spreading, which is a material shortcoming of fasteners provided at the present time which present spaced legs resting directly against the wall. The two straight spacing elements 3 are 95 formed into one unit with the base and are of the same strength as the base and are sufficiently strong to resist any blow of a hammer necessary to drive the nail, particularly when reinforced by the indenture 100 12. The saddle 4 allows the wire to lie in the same in its natural position without being stretched or bent out of shape and without coming in contact with any sharp corners which might tend to cut the wire. 105 It stands to reason that a fastener of this character may be made of very light material without losing its advantageous features.

Attention is further called to the fact 110 that the perforation 7 in the top of the device is dimensioned to tightly fit the nail so

that the form and the nail may be sold in the market as a unit and the carpenter need not first assemble the form and the nail but merely picks up the unit, places the point of the nail against the wall and strikes the head with a hammer.

I claim:

1. Means for fastening a wire screen in spaced relation to a wall comprising a hollow, rectangular form open on two opposing sides presenting a solid flat base adapted to be placed against the wall, slanting sides and a top forming a saddle, with a single central perforation in the top and a registering perforation in the base allowing a nail to be driven through the form into the wall and allowing a strand of wire to be confined in the saddle by the head of the nail.
2. Means for fastening a wire screen in spaced relation to a wall comprising a hollow, rectangular form open on two opposing sides presenting a solid flat base adapted to be placed against the wall, slanting

sides and a top forming a saddle, with a single central perforation in the top and a registering perforation in the base allowing a nail to be driven through the form into the wall and allowing a strand of wire to be confined in the saddle by the head of the nail, the perforation in the top being dimensioned to just fit the nail so as to allow form and nail to be handled in the market and to be operated as a unitary structure.

3. Means for fastening a wire screen in spaced relation to a wall comprising a hollow, rectangular form open on two opposing sides presenting a solid flat base adapted to be placed against the wall, slanting sides and a top forming a saddle, with a single central perforation in the top and a registering perforation in the base allowing a nail to be driven through the form into the wall and allowing a strand of wire to be confined in the saddle by the head of the nail, the slanting sides being indented to better resist collapse under the blow of a hammer.

ISAAC PETERSON.
